UNITED STATES PATENT OFFICE.

JOHN FRANCES HUGHES, OF TORONTO, ONTARIO, CANADA.

FLUSHING DEVICE FOR HYDRAULIC ELEVATORS.

1,162,165.

Specification of Letters Patent.

Patented Nov. 30, 1915.

Application filed June 4, 1913. Serial No. 771,688.

To all whom it may concern:

Be it known that I, JOHN FRANCES HUGHES, resident of 43 Empress Crescent, in the city of Toronto, county of York, 5 Province of Ontario, in the Dominion of Canada, chief engineer, have invented certain new and useful Improvements in Flushing Devices for Hydraulic Elevators, of which the following is a specification.

10 The invention relates to improvements in flushing devices for hydraulic elevators as described in the present specification and illustrated in the accompanying drawings that form part of the same.

15 The invention consists essentially in the novel means employed whereby a stream of water is directed into the plunger shaft to force the sediment from the bottom thereof.

20 The objects of the invention are to devise a quick and effective means of clearing out the accumulation of sand and other sediment in the bottom of the plunger shaft, to avoid delays in the elevator service, and generally to provide a simple cheap and 25 durable flushing device.

In the drawings, Figure 1 is a plan view of the arrangement of the pipes in relation to the plunger shaft. Fig. 2 is a vertical section view of the plunger shaft and 30 piston and plunger, showing the pipes utilized in this flushing device.

Like numerals of reference indicate corresponding parts in each figure.

Referring to the drawings, 1 is the plunger shaft in which the plunger 2 operates as customary in hydraulic elevators, said plunger carrying at its upper end the platform 3.

4 is the inlet and outlet pipe having at the 40 upper end the customary feed pipe 5, and discharge pipe 6 said inlet and outlet pipe 4 extending downwardly and entering the plunger shaft 1 at 7.

8 is a branch waste pipe from the inlet 45 and outlet pipe 4 leading to the drain or any suitable place and having therein a suitable cut-off.

9 is a valve cutting off the inlet and outlet of water from the supply pipe 4 between the 50 source of supply and the entrance to said waste pipe 8.

10 is a flushing pipe having the upper end thereof 11 extending outwardly from the plunger 2 adjacent to the upper end thereof, said flushing pipe 10 here shown inside

the piston and moving up and down with the travel of the piston though it must be understood that this pipe in many instances will be outside the plunger shaft in which case it will not move up and down with the 60 piston.

The upper end 11 of the flushing pipe 10 terminates in the flexible joint connection 13.

14 is a hose having corresponding flexible joint connection at the end thereof adapted 65 to be secured to the flexible joint 13, said hose at the other end being secured to a suitable source of supply of water, preferably the supply pipe beyond the valve 9.

It will be thus seen that on opening the 70 valve in the feed pipe 5 and closing the valve 9 and turning the water into the flushing pipe 10, a considerable stream of water will flow down said flushing pipe into the bottom of the plunger shaft 1, and as the 75 ordinary supply has been cut off, the ingress of water to the said plunger shaft below the plunger 2, will drive said water up to and into the inlet and outlet pipe 4 as far as the branch exhaust pipe 8 and out through said exhaust 80 pipe to the drain, and as this stream is continually flowing it will carry away with it all the sand or other sediment at the bottom of the plunger shaft. This stream carrying 85 away the sand flows into the waste pipe 8 and from there on to the drain.

This invention is manifest to those who are accustomed to cleaning out hydraulic elevators, for, under the system now used, it takes the best part of a day to clean out 90 the plunger shaft, whereas in the present invention it is only a matter of minutes and the elevator can then be set running again without interference with or taking away any of the parts during the flushing process. 95

What I claim is:—

1. The combination with the plunger shaft of a hydraulic elevator, a plunger operating in said shaft and a source of water supply, of a flushing pipe extending to the under side of said plunger within said plunger, a pipe connected with the upper end of said flushing pipe, a flexible tube connecting the upper pipe to the water supply and an exhaust pipe. 100

2. In a flushing device for hydraulic elevators, a flushing pipe extending downwardly within the plunger shaft and communicating with the lower end of the plunger shaft, an inlet and outlet pipe extend- 110

ing outwardly from the said plunger shaft, and a waste pipe extending from said inlet and outlet pipe.

3. In a flushing device for hydraulic elevators, a flushing pipe extending downwardly and communicating with the lower end of said plunger shaft and at its upper end adapted to be connected to a suitable source of supply, an inlet and outlet pipe 10 extending outwardly from the plunger shaft and connected to a suitable source of supply, a waste pipe branching from said inlet and outlet pipe intermediate of the length thereof and a cut off valve in said inlet and outlet pipe between said branch pipe and the source of supply.

4. In a flushing device for hydraulic elevators, a flushing pipe extending downwardly and communicating with the lower 20 end of the plunger shaft, an inlet and outlet pipe extending outwardly from plunger shaft and suitably connected to discharge and feed pipes, a pipe connecting said feed pipe with said flushing pipe, a waste pipe 25 branching from said inlet and outlet pipe

adjacent to the plunger shaft, and a cut off valve in said inlet and outlet pipe between said branch pipe and said feed pipe.

5. In a device of the class described, in combination a plunger shaft, a plunger, a 30 flushing pipe extending downwardly through the interior of said plunger and the bottom thereof and projecting outwardly from said plunger at the upper end, said upper end terminating in a flexible joint member, an inlet and outlet pipe, a branch waste pipe from said inlet and outlet pipe, a cut off valve in said inlet and outlet pipe between said branch waste pipe and the supply and a hose having a flexible joint member on one 35 end connected to the aforesaid flexible joint member, said hose at the other end being connected to a suitable source of supply.

Signed at the city of Toronto, this fifth day of April 1913.

JOHN FRANCES HUGHES.
